Inventor:
By: Claude M. Dibble,
Munday, Clarke & Carpenter, Atty.

UNITED STATES PATENT OFFICE.

CLAUDE M. DIBBLE, OF JOLIET, ILLINOIS, ASSIGNOR TO MOORE BROTHERS COMPANY, OF JOLIET, ILLINOIS, A CORPORATION OF ILLINOIS.

HINGED CLOSURE.

Application filed July 17, 1926. Serial No. 123,046.

This invention relates in general to hinged closures for stoves and the like, and more particularly to a door and frame formed to cooperate therewith that are particularly adapted for use on ovens and the like.

An important object of the invention is to provide a door that may be assembled to and disassembled from a frame from the outside and such a door and frame that will be of simple construction.

Another important object of the invention is to provide such a door in which the hinge pins are located entirely within the front face of the door frame so that there will be no projections on the face of the frame and such a construction that may be readily attached and detached by merely removing separable parts of the frame and lifting the door bodily therefrom.

Another important object is to provide a simple hinge construction for doors or closures of this type and one in which a type of coil spring may be used that is already in common use in stoves.

Numerous other objects and advantages of the invention will be apparent as it is better understood from the following description, which, taken in connection with the accompanying drawings, discloses a preferred embodiment thereof.

Referring to the drawings,

Figure 1 is a front elevational view of a portion of a stove and showing a door and frame embodying my invention,

Fig. 2 is a section taken substantially on line 2—2 in Fig. 1,

Fig. 3 is a rear elevational view of a corner of the door and a portion of the frame and showing the hinge construction on an enlarged scale,

Fig. 4 is a section taken substantially on line 4—4 in Fig. 3,

Fig. 5 is a perspective view showing the inside form of the cover plate or a frame part,

Fig. 6 is a section taken substantially on line 6—6 in Fig. 1 and showing the door in open position, and

Figs. 7 and 8 are sections taken on lines 7—7 and 8—8 respectively in Fig. 1.

To illustrate my invention I have shown a door 11 and a door frame 12. The door 11 may be of any suitable shape, form or construction, and in the present instance is

shown substantially rectangular. A hinge pin 13 is provided that may be a separate rod or the like extended through the door and laterally therefrom at each side, or may be provided in any suitable manner, such as by casting separate pin portions integral with the frame and to extend laterally therefrom at each side. The hinge pin is preferably fluted or notched as at 14 to provide a seat in which an end 15 of a spring 16 may engage. The spring 16 may be a coil spring or any other suitable spring that may be positioned over the pin 13, and one is preferably provided for each pin. An end 17 of the spring 16 is formed to extend laterally from the spring and to engage the frame in any suitable manner or substantially as shown.

The frame 12 may be of any suitable form and may be formed of one or more pieces as desired and for attachment to the stove in any suitable manner. In the preferred construction the frame 12 is cast in one piece and with a substantially flat front face. A portion of the frame and at each side thereof, that may be of any suitable shape or outline, is set back and formed to provide a hinge pin seat or a one-half bearing 18 for the hinge pin 13, and a cover plate 19 is formed to fill in the set-back portion of the frame and for attachment to a stop web 21 thereof by means of a screw 22 or a like fastening device, so that it may be readily removed therefrom and will hold the hinge pin 13 against the bearing portion 18 of the frame, a web 23 of the plate 19 being formed substantially as shown (Fig. 5) and having a portion 24 arranged to embrace a side of the pin. A portion 25 extends laterally from the plate and is apertured as at 26 to receive the screw or fastening device 22 that is preferably threaded into a recessed or set-back portion of the web 21. One or more lugs 27 may be formed on the cover plate for supporting the outer edge thereof against externally applied forces. The set-back portion of the frame 12 on at least one side, and preferably both, is formed or cut away substantially as at 31 (Fig. 3) to provide an opening into which the hinge pin and spring may be inserted and a wall 32 against which the laterally extending portion 17 of the spring 16 may engage. The upper part of the cut away portion 31 pro-

vides a means of releasing the portion 17 of the spring from behind the wall 32. A web portion of the door is preferably extended down to adjacent the hinge pin 13 to provide a projection 33 suitably formed for limiting the downward movement of the door.

Where two springs 16 are used these springs are assembled on the hinge pins 13 substantially as illustrated. The hinge pins are positioned against the one-half bearing portions 18 at each side of the frame. The lateral projection 17 of the spring 16 is then moved through the cut away portion 31 (Figs. 3 and 8) and hooked behind the wall portion 32, which is preferably provided with a notch 34 in which the portion 17 of the spring may slide longitudinally during operation, and the cover plate 19 may then be positioned and secured by means of the screw 22. It will be obvious from the above described assembly that to disassemble the door from the frame it is only necessary to remove the cover plates 19, to disengage the laterally extending portion 17 of the spring 16 from behind the wall 32 with any suitable tool such as a screw driver or the like, and to lift the door bodily from the frame, and that when the door is assembled there will be no projections on the face of the frame that will be unsightly and difficult to clean, and therefore unsanitary. The springs 16 may be omitted if desired, and are provided to urge the door toward closed position or to relieve the weight or counter-balance the door during operation. Any suitable handle 41 may be provided for opening the door.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A hinged closure for stoves and the like comprising, a door, a door frame, said door being provided with a laterally extending hinge pin, a spring mounted on said hinge pin and having a portion extending laterally therefrom, said frame being formed to provide a seat for the hinge pin and a projection for holding the laterally extending portion of the spring, and a cover plate arranged for attachment to the frame and for holding the hinge pin against the seat in the frame.

2. A hinged closure for stoves and the like comprising, a frame having bearing portions formed in the front face thereof, a closure having a hinge pin extending laterally therefrom to engage in the bearings

in said frame, a spring mounted on said hinge pin and engaging a stove portion to urge said closure yieldably toward closed position, and a cover plate formed to hold said hinge pin against the bearings and for attachment to the frame.

3. A hinged closure for stoves and the like comprising, a frame having bearing portions formed in the front face thereof, a closure having hinge pins extending laterally therefrom to engage in the bearings in said frame, a spring mounted on said hinge pin and engaging a stove portion to urge said closure yieldably toward closed position, and cover plates formed to hold said hinge pins against the bearings and for attachment to the frame, the front face of said cover plates being formed in accordance with the front face of the frame and to provide a continuation thereof.

4. A hinged closure for stoves and the like comprising, a frame having bearing portions formed in the front face thereof, a closure having hinge pins extending laterally therefrom to engage in the bearings in said frame, a spring mounted on said hinge pin and engaging a stove portion to urge said closure yieldably toward closed position, and cover plates formed to hold said hinge pins against the bearings and for attachment to the frame, said cover plates lying wholly within the plane of the front surface of the frame.

5. A hinged closure for stoves and the like comprising, a frame having bearing portions formed therein, a closure having a hinge pin extending laterally therefrom, a spring, and a cover plate for holding said hinge pin against said bearings, said hinge pin being fluted and said spring being arranged to engage in the flute in said pin and to engage the frame for yieldably holding said door in closed position.

6. A hinged closure for stoves and the like comprising, a frame having bearing portions formed therein, a closure having hinge pins extending laterally therefrom, a spring, and cover plates for holding said hinge pins against said bearings, a said hinge pin having a notch in the periphery thereof and said spring being positionable over the hinge pin and formed to engage in said notch and to engage the frame for urging the door toward closed position.

7. A hinged closure for stoves and the like comprising, a frame, and a hinged closure pivotally mounted therein, said closure including a hinge pin journaled in the frame at a point located entirely within the front face thereof and having a spring mounted thereon and engaging the frame for urging the closure toward closed position, said closure being removable from the frame by a forward movement thereof.

8. A hinged closure for stoves and the like

comprising, a frame, and a hinged closure pivotally mounted therein, said closure including a hinge pin journaled in the frame at a point located entirely within the front face thereof and having a spring mounted thereon and engaging the frame for urging the closure toward closed position, said closure being removable from the frame by a forward movement thereof and the removal of frame parts.

9. A hinged closure for stoves and the like comprising, a door having hinge pins extending laterally therefrom, a frame having a portion formed to provide a one-half bearing for each hinge pin and located rearwardly of the front face thereof, a spring mounted on said hinge pin and engaging a portion of said frame to urge said closure to normally closed position, and parts detachably secured to the frame and providing the remainder of the bearings for the pins.

10. A hinged closure for stoves and the like comprising, a door having hinge pins extending laterally therefrom, a frame having a portion formed to provide a one-half bearing for each hinge pin and located rearwardly of the front face thereof, a spring mounted on said hinge pin and engaging a portion of said frame to urge said closure to normally closed position, and separable parts formed to hold the hinge pins against

said one-half bearings and to lie entirely within the front face of the frame.

11. A hinged closure for stoves and the like comprising, a door having hinge pins extending laterally therefrom, a frame formed to provide bearings for said hinge pins, and a coil spring arranged over each said hinge pin and engaging in a recess therein, said coil springs having laterally extending portions for engaging the frame.

12. A hinged closure for stoves and the like comprising, a door having hinge pins extending laterally therefrom, a frame formed to provide bearings for said hinge pins, and a coil spring arranged over each said hinge pin and engaging in a recess therein, said coil springs having laterally extending portions for engaging the frame and said frame having removable parts for facilitating the removal of the door.

13. A hinged closure for stoves and the like comprising, a door having hinge pins extending laterally therefrom, a frame formed to provide bearings for said hinge pins, and a coil spring arranged over each said hinge pin and engaging in a recess therein, said coil springs having laterally extending portions for engaging the frame, said frame having removable parts for facilitating the removal of the door together with the hinge pins and springs.

CLAUDE M. DIBBLE.
